UNITED STATES PATENT OFFICE.

FANNY GILLETTE, OF NEW YORK, N. Y.

DESIGN FOR A FAN.

SPECIFICATION forming part of Design No. 15,112, dated July 1, 1884.

Application filed April 25, 1884. Term of patent 3½ years.

To all whom it may concern:

Be it known that I, FANNY GILLETTE, a citizen of the United States, residing in the city of New York, in the county and State of New

5 York, have invented and produced a new and original Design for an Advertising-Fan, of which the following is a specification, reference being had to the accompanying drawing, forming a part thereof.

10 This design is intended to be represented upon fans.

The distinguishing feature of my design consists in a representation of patchwork on the face (and also on the back, if desired) of the 15 fan, with lines representing the seams and ornamental or fancy stitches, substantially as shown in the accompanying drawing.

In said drawing, A represents the body of the fan, and B any suitable handle. a a a represent the separate or individual patches. b

b b are thin lines representing the seams between the several patches, and c c c are thicker lines representing ornamental or fancy or embroidery-stitches.

I do not restrict myself to the precise position of the lines in relation to each other, as represented in said drawings, as it is obvious that the same may be slightly changed without materially altering or changing the general effect. 25

I claim—

The design for a fan herein shown and described, the same consisting of the spaces a a a, to represent patches, the lines b b b representing seams, and the lines c c c representing 35 fancy or embroidery stitches.

FANNY GILLETTE.
